US0D1073611S

(12) **United States Design Patent** (10) **Patent No.:** **US D1,073,611 S**
(45) **Date of Patent:** **** May 6, 2025**

(54) **BATTERY HOLDER**

(71) Applicant: **Infinity X1 LLC**, Las Vegas, NV (US)

(72) Inventor: **Dennis Bertken**, Las Vegas, NV (US)

(73) Assignee: **INFINITY X1 LLC**, Las Vegas, NV (US)

(**) Term: **15 Years**

(21) Appl. No.: **29/930,482**

(22) Filed: **Feb. 29, 2024**

(51) **LOC (15) Cl.** **13-02**

(52) **U.S. Cl.**

USPC **D13/119**

(58) **Field of Classification Search**

USPC D13/102–106, 110, 118, 119, 184, 199;

Primary Examiner — Leanne Was-Englehart

(74) *Attorney, Agent, or Firm* — Jeffer Mangels Butler & Mitchell LLP; Brennan C. Swain, Esq.

(57) **CLAIM**

The ornamental design for a battery holder as shown and described.

DESCRIPTION

FIG. 1 is a perspective view of the battery holder, showing my new design;

FIG. 2 is a front side elevational view thereof;

FIG. 3 is a rear side elevational view thereof;

FIG. 4 is a left elevational view thereof;

FIG. 5 is a right elevational view thereof;

FIG. 6 is a top plan view thereof;

FIG. 7 is a bottom plan view thereof;

FIG. 8 is a perspective view of the battery holder, showing my new design;

FIG. 9 is a front side elevational view thereof;

FIG. 10 is a rear side elevational view thereof;

FIG. 11 is a left elevational view thereof;

FIG. 12 is a right elevational view thereof;

FIG. 13 is a top plan view thereof; and,

FIG. 14 is a bottom plan view thereof.

The broken lines in the drawings depict portions of the battery holder that form no part of the claimed design.

1 Claim, 8 Drawing Sheets
